MACHINE FOR PERFORMING NAILING AND
LIKE FASTENING OPERATIONS

John Hoza, Zlin, Czechoslovakia

Application October 29, 1938, Serial No. 237,768
In Czechoslovakia October 16, 1937

3 Claims.

(Cl. 1-18)

The invention relates to improvements in machines for performing nailing and like fastening operations and especially for performing nailing operations on the heels of footwear during the manufacture thereof.

With more particularity, the invention is concerned with means for mounting the orifice member, (from which the fastening elements are delivered) on its support and it is an object of the invention to permit the orifice member to be readily removed, and as readily mounted on its support, these operations being required fairly frequently—on breaking of one of the fastening elements in the delivery channel of the orifice member for example. If the removal and mounting of the orifice member on such an occasion is a lengthy procedure it entails a complete interruption of all the stages of production associated with the fastening operations.

A second object of the invention is to ensure that, despite the rapidity with which the orifice member may be mounted on its support, it is yet accurately positioned. This obviates uneven wear of the hammers which eject the fastening elements from the orifice member or prevents a stoppage of the machine due to the hammers jamming in the delivery channels, either of which consequences might arise from an inaccurate positioning of the orifice member.

It is a third object of the invention to permit the orifice member to be mounted on its support without the use of screws or the like.

An example of the invention is shown in the drawing, which shows:

Fig. 1 is an elevation of an orifice member mounted on the turret, and showing the delivery channels, hammers and the other mechanisms;

Fig. 2 is a detail view of part of the mounting; and Fig. 3 a cross section on the line A—A of Fig. 2.

Referring to the drawing:

An orifice member 2 for delivering the nails is suspended on the support 1 in such a way that the outlet orifices of the channels 3 in the member 2 lie exactly over corresponding openings 4 of the reaction member 5. This member 5 is connected to the support 1 in such a way that, during the operation of the nailing machine, it is moved conjointly with the orifice member 2. In addition, hammers 6 are provided on the support 1, the number of hammers corresponding to the number of channels 3 in the orifice member. The front surface of the support 1 is steeply inclined so that the orifice mem-

ber, which has a surface to engage the inclined surface of the support, has when mounted in position the inclination requisite for accurately driving in the fixing nails. On this inclined surface there is a recess 7 from opposite ends of which keyways extend, in which keyways fit two keys 8 (Fig. 2). These keys 8 are of dovetail formation as shown in Fig. 3, and the keyways with which they are engaged are of corresponding construction so that the member 2 is slid- 10 ily locked to the support 1 when the keys are engaged in the keyways. The keys are located on the orifice member 2 beyond and spaced from opposite ends of a projection 13 which projects into the recess 7, but is however shorter by a 15 given extent than the recess, so that the keys can move in the keyways, and be disengaged therefrom when the member 2 reaches its limit of movement in an upward direction. The end walls of the recess 7 provide stops for abutment 20 with the projection 13 to limit upward and downward movement of the member 2. To normally prevent its upward movement, the orifice member 1 is secured on the support 2 by a projection 9 which rests on a seat formed by the upper edge of the inclined surface of the support 1 and is fixed there by a pivoted latch 10 which is turnably supported on the pivot 11 in the support 1 and is urged to its projection-engaging position by the spring 12. This mode of 25 suspension is simple and is dependable in that the orifice member is secured more firmly by the latch 10 in proportion as the orifice member is stressed by the impact so that the orifice member holds better the greater is the pressure applied to it from underneath (from the heel).

The procedure on mounting and removing the orifice member 2 is very simple, easy, and speedy. The operator moves the latch 10 on the support 1, pushes the orifice member upwardly until 40 the projection 13 on the orifice member engages with its upper edge on the upper face of the recess 7. During this movement, the keys 8 slide through the keyways and out of engagement therewith. Thereupon the orifice member 45 is swung out away from the support 1 and is pulled downwards until the hammers 6 slide out of the channels 3 in the orifice member, which is then free. The mounting of the orifice members is effected by the same procedure but with 50 55 the steps in reverse order.

The use of an orifice member mounted in this way is very simple and at the same time very economical, the orifice member having a longer life than those at present in use.

I claim:

1. In a machine for performing nailing and like fastening operations and comprising an orifice member for delivering fastening elements and a support for the orifice member, the orifice member and support having surfaces adapted to interengage face to face: means for mounting the orifice member on the support said means comprising a projection on the orifice member and a seat on the support to receive the projection; a pivoted latch on the support, the latch being adapted to engage the projection; resilient means urging the latch to its projection-engaging position; and a positioning connection between the orifice member and the support, the connection being constituted by key and keyway elements.
2. A machine for performing nailing operations in the manufacture of footwear comprising an orifice member formed with delivery channels and outlet orifices for the channels; hammers for ejecting nails from the orifices; a support for the orifice member having a steeply in-

clined surface, the orifice member having a surface to engage face to face with the support surface; a projection on the orifice member; seat on the support to receive the projection and thereby hold the orifice member removably suspended on the support; a pivoted latch on the support to engage the projection; resilient means urging the latch to its projection-engaging position; a reaction member on the support formed with openings to register with the outlet orifice on the orifice member; a keyway on the support and a key on the orifice member complementary to and engaging the keyway and positioning the orifice member so that its outlet orifices are in exact registry with the openings in the reaction member.

3. The machine claimed in claim 2, and comprising also an abutment on the orifice member and stops on the support defining limits of up and down movement of the engaging surfaces on the orifice member and support.

JOHN HOZA.
